WAWRZYNIEC SLEZAK, OF BRIDGEPORT, CONNECTICUT.

ELECTRIC STOP-MOTION DEVICE FOR LOOMS.

1,321,762.

Specification of Letters Patent.

Patented Nov. 11, 1919.

Application filed June 18, 1919. Serial No. 305,004.

To all whom it may concern:

Be it known that I, WASYL LAWRUSHKO, a citizen of Ukraine, residing at Bridgeport, in the county of Fairfield and State of Connecticut, have invented certain new and useful Improvements in Electric Stop-Motion Devices for Looms, of which the following is a specification.

The primary object of the present invention is to provide an electric stop motion device for looms wherein an electric circuit is adapted to be established for purposes of stopping the loom when the fabric passing therethrough is not traveling in the proper manner.

A further object of the invention is to provide an electric stop motion device for looms that coöperates with the fabric passing therethrough to guide the same during its movement and which is adapted to be operated upon a reverse movement thereof to complete an electric circuit and stop the operation of the loom.

With the above and other objects in view, the invention consists in the combination and arrangement of parts herein fully described in connection with the accompanying drawings and in which like characters of reference indicate similar parts throughout the several views.

In the drawings,

Figure 1 is a longitudinal sectional view of the guide roller constructed in accordance with the present invention and embodying mechanism for completing an electric circuit,

Figs. 2 to 13 are cross sectional views taken on corresponding section lines on Fig. 1 showing the several elements forming the guide roller,

Fig. 14 is a detached side elevational view of the tubular screw,

Fig. 15 is a diagrammatic view showing the split fabric passing through the loom over the feed and guide rollers in its proper movement, and

Fig. 16 is a diagrammatic view, similar to Fig. 15 with the feeding roller improperly engaging the fabric thread through the loom and causing a reverse movement of the guide rollers as illustrated for purposes of stopping the loom.

In the art to which this invention pertains, with particular reference to the manufacture of velvet and like fabric, there is employed a feed roller having a plurality of

pins or pickers upon the periphery thereof adapted for engaging the fabric while passing through the loom to insure the proper movement thereof and to place the same under tension while leaving the loom. Unless the pins are of perfect formation, the fabric passing through the loom will be caught by said pins and improperly retained and carried beyond the usual point of leaving the feed roller as illustrated in Fig. 16 and with continued rotation of the feed roller, the fabric will be wound thereon, both from the receiving roller and from the loom which renders this material worthless for the purpose intended as well as necessitating the severing of the other ply thereof so that additional time is necessary for again starting the initial passage of the fabric on the receiving rollers as well as a serious financial loss. The present invention aims to overcome this defect by associating an electric switch mechanism with one of the guide rollers in which the cylinder of the guide roller is provided with a plurality of pins for engagement with the surface of the fabric to insure a movement thereof in the reverse direction as indicated in Fig. 16 so that an electric circuit will be instantly completed upon a slight reverse movement of said guide roller to cause the machine to be stopped instantly, while during the proper movement of the fabric through the machine, the guide roller provided with the circuit completing device rotates in the usual manner with the circuit open.

Describing the invention more in detail, particular reference will first be had to Figs. 15 and 16 which show diagrammatically the traveling movement of the fabric through the loom, it being understood that the present winding mechanism is associated with a machine for manufacturing velvet or any similar material of two-ply construction adapted for transverse severing, there being provided as illustrated, a pair of feed rollers 1 provided on their peripheries with a plurality of pins 2 for engagement with the fabric strips 3 that are separated by the knife 4 as illustrated in said figures. The fabric 3 in passing to the receiving rollers 5, and upon leaving the feed roller 1 pass over guide rollers 6 and 7, the fabric 3 being held in engagement with the guide rollers 7 by the auxiliary rollers 7' and during the proper movement of the fabric

through the receiving mechanism, the guide roller 7 moves in the direction indicated by the arrow in Fig. 15. The gist of the present invention particularly resides in the 5 specific construction of the guide roller 7 which will now be described in detail.

The guide roller 7 is shown in detail in Figs. 1 to 14 and includes a hollow cylindrical casing 8 open at each end and provided upon the periphery thereof with a plurality of pins 9 arranged thereon in any desired formation. One end of the casing 8 is closed by a plug 10 secured in said end by a set screw 11 illustrated in Fig. 2 while 15 an opening is provided centrally thereof to receive the stub axle 12 carried by the block 13 and upon which axle, the plug 10 and casing 8 are rotatably mounted, lateral movement of the plug and casing upon the 20 axle 12 being prevented by the ring 14 adjustably secured to said axle between the block 13 and plug 10.

As illustrated in Fig. 3, the inner wall of the casing 8 is uninterrupted and is 25 adapted to receive in the open end thereof, the cylinder 15 that is retained therein and held immovable relative to said casing by a set screw 16 shown at the right hand side of the casing 8. Diametrically opposite 30 key-way slots 17 are formed upon the inner face of the cylinder 15 as shown in Figs. 1 and 5 for purposes presently to appear.

A block 18 is secured in the left hand end of the cylinder 15 by a set screw 19 illustrated in said figures and forms a bearing for one end of an expansion coil spring 20 contained within said cylinder. A cup-shaped member 21 has the end wall 22 thereof engaging the other end of said coil 40 spring 20 and is slidably received in the cylinder 15, being capable of free longitudinal movement and prevented from relative rotary movement by the keys 23 formed upon diametrically opposite sides of the 45 periphery thereof and extending longitudinally for sliding reception in key-way slots 17 of the cylinder. With this construction, it will be seen that the cup 21 is capable of sliding movement in the cylinder and guided in such movement by the keys 23 engaging the slots 17 which will prevent rotary movement of said cup and cause the same to be revolved with the cylinder 15 and casing 8.

50 55 A tubular screw 24 shown in Figs. 1 and 14 includes a plain body portion as illustrated with an annular flange 25 intermediate the ends thereof and with a threaded head 26 at its forward end, the tubular screw 24 being adapted to have its head 26 inserted in the hollow portion of the cup 21 with lugs 27 shown in Figs. 1 and 7 projecting from opposite sides of the inner face of said cup for reception in the grooves 65 of said screw head while the end of the

tubular screw 24 outwardly of said flange 25 is supported in the fixed gasket bearing 28 shown in Figs. 1 and 10, which gasket is fixed to the cylinder 15 by the set screw 29.

A support for the right hand end of the 70 casing 8 includes a rectangular plate 30 corresponding to the plate 13 and secured to a fixed support, and carries a forwardly projecting arm 31 having a cylindrical bearing 32 into which the rearwardly projecting end 75 of the tubular screw 24 is received as shown in Figs. 1 and 11, the screw being secured immovable relative to said support by the set screws 33.

An insulating bushing 34 of tubular formation extends into the tubular screw 24 and terminates at a point adjacent the screw head thereof, the rear end of said insulating bushing projecting outwardly of said screw and having an offset portion 35 85 for the reception of a threaded terminal plug 36. A short metal tube 37 is inserted in the outwardly projecting end of the bushing 34 and is engaged by the terminal screw 36. A contact needle 38 slidably projects 90 through said insulator bushing 34 and is provided with a pair of collars 39 and 40, an expansion coil spring 41 surrounding said contact needle 38 between the metal tube 37 and collar 40 while a closure plug 42 is inserted in the inner end of the insulator bushing 34 to be engaged by the collar 39 to limit the forward movement of the contact needle caused by the spring. A bracket 43 is carried by the attaching plate 100 30 and supports a terminal plug 44 while circuit wires 45 are connected to the terminal plugs 36 and 44 forming the lines of the circuit. The journal bearings for the casing 8 and parts that rotate therewith 105 include the stub axle 12 at the left hand end thereof and the tubular screw 24, it being noted that the gasket bearing 28 rotates with the cylinder and casing 8 while the tubular screw 24 remains stationary by 110 being secured by the set screw 33 to the stationary bracket 31.

During the operation of the device, assuming that the fabric 3 is properly traveling over the feed roller 1 and with the guide 115 roller 7 rotating in the direction indicated by the arrow in Fig. 15, the cup 21 revolving with the cylinder and casing 8 will be moved toward the left by having the lug 27 thereof engaged in the screw head 26 of 120 the screw so that the cup will be held spaced from the contact needle 38, during which movement, the keys upon the outer face of said cup slide in the cylinder grooves 17 and the cup during such movement is cushioned 125 by the spring 20 and maintained forwardly positioned by said screw and the spring 46 surrounding the screw between the block 28 and open end of said cup, the circuit in this position of the parts being open.

Should the fabric strips 3 improperly engage the feed rollers 1 as illustrated in Fig. 16 as by being retained by the pins upon the peripheries of the cylinders and, wound 5 upon said cylinders as illustrated, guide rollers 7 will be reversely rotated as indicated by the arrow in Fig. 16 and during this movement, the cup 21 rotating with the casing 8 will have the lugs 27 upon the 10 inner face thereof engaged in the screw head 26 and moved thereover to compress the spring 46 and be assisted in its movement by the spring 20, and during which movement the head 22 of said cup will engage the 15 forwardly projecting end of the contact needle 38 to complete the electric circuit from the plug 36, metal tube 37, needle 38, cup 21 and grounded through the remaining mechanism to the plug 44, the circuit being 20 completed to cause an instant stopping of the loom so that the improper tracting of the material may be stopped and the needed repairs made. With this construction, it will be seen that a simple and effective means is 25 provided for stopping the loom instantly upon the improper movement of fabric passing over the guide rollers as with only a slight winding of the fabric upon the feed roller, the same may be repaired without 30 serious damage and loss of time as would be the case if the material were allowed to wind for a considerable length upon said feed rollers.

While I have herein shown what are believed to be the preferred embodiments of my invention, it is nevertheless to be understood that minor changes may be made in the form, combination and arrangement of parts without departing from the spirit and 40 scope of the invention as claimed.

What I claim as new is:—

1. The combination with the rotatable guide roller of a loom, of means associated with the guide roller for stopping the loom 45 upon a reverse rotation of the guide roller, said means including a plurality of normally inoperative coöperating elements, and means engaging one of said elements to cause the coöperation of said coöperating 50 elements for stopping the loom when the roller is reversely rotated.

2. An electric stop motion device for looms including a rotatable guide roller, a contact carried thereby and a stationary 55 contact associated therewith, and means made operative upon a reverse rotation of said roller to bring the contacts into engagement.

3. An electric stop motion device for 60 looms including a rotatable casing, fixed elements arranged in spaced relation therein, a movable contact within said casing between the fixed elements, cushion means at opposite sides of the contact and 65 engaging the fixed elements, a stationary

contact associated with said casing, and means for causing the movable contact to engage the stationary contact.

4. The combination with a loom guide roller, of a stationary electric contact point 70 and a rotatable and slidable contact point, and means for causing the latter point to be shifted upon a reverse rotation of said roller to cause engagement of the contact points.

5. An electric stop motion device for looms 75 including a rotatable casing, an axle bearing at one end thereof, a tubular screw upon which the other end is journaled and electric contacts carried by the screw and casing and means adapted to be operated upon a reverse rotation of the casing to cause an engagement of the contacts.

6. An electric stop motion device for looms comprising a guide roller formed of a cylindrical casing, an axle bearing at one 85 end thereof, a tubular screw extending into the other end of said casing upon which said casing is rotatably mounted, a fixed support for said screw, an electric terminal post carried by said support, another post carried by 90 said screw, coöperating contact points carried by said screw and casing and means adapted to cause the contact points to be brought into engagement when said casing is reversely rotated. 95

7. An electric stop motion device for looms comprising a guide roller formed of a cylindrical casing, an axle bearing at one end thereof, a tubular screw extending into the other end of said casing upon which said 100 casing is rotatably mounted, a fixed support for said screw, an electric terminal post carried by said support, another post carried by said screw, coöperating contacts carried by the screw and casing, and coöperating 105 means carried by the casing contact, the screw and the casing to cause the casing contact to be rotated with the casing and be adapted for sliding movement into engagement with the contact carried by the screw 110 when said casing is reversely rotated.

8. An electric stop motion device for looms comprising a guide roller formed of a cylindrical casing, an axle bearing at one 115 end thereof, a tubular screw extending into the other end of said casing upon which said casing is rotatably mounted, a fixed support for said screw, an electric terminal post carried by said support, another post carried by 120 said screw, a needle contact resiliently supported in said tubular screw, a cup rotatable with and slidably received in said casing constituting a contact point and normally out of engagement with said needle, and means carried by said cup in engagement with said screw for causing the cup to move into engagement with said contact needle when the casing is reversely rotated. 125

9. An electric stop motion device for looms comprising a guide roller formed of a 130

cylindrical casing, an axle bearing at one end thereof, a tubular screw extending into the other end of said casing upon which said casing is rotatably mounted, a fixed support for said screw, an electric terminal post carried by said support, another post carried by said screw, a needle contact resiliently supported in said tubular screw, a cup rotatable with and slidably received in said casing constituting a contact point and normally out of engagement with said needle, lugs formed upon the inner face of the cup extending into the grooves of said screw adapted when said cup is rotated with the casing to move the cup out of contact with the contact needle and to cause said cup to engage said contact needle when the casing is reversely rotated.

10. An electric stop motion device for looms comprising a guide roller formed of a cylindrical casing, an axle bearing at one end thereof, a tubular screw extending into the other end of said casing upon which said casing is rotatably mounted, a fixed support for said screw, an electric terminal post carried by said support, another post carried by said screw, a tensioned contact needle carried by said tubular screw, means for insulating the same from said screw, a contact cup slidably received in said casing and rotatable therewith, connections between said cup and screw for causing said cup to move in opposite directions upon opposite rotation of the casing and cushioning means for the cup arranged at opposite sides thereof.

11. An electric stop motion device for looms comprising a guide roller formed of a cylindrical casing, an axle bearing at one end thereof, a tubular screw extending into the other end of said casing upon which said casing is rotatably mounted, a fixed support for said screw, an electric terminal post carried by said support, another post carried by said screw, a tubular insulating bushing within said tubular screw, a contact needle resiliently mounted in said bushing, a contact cup slidably keyed within said casing to rotate therewith and cooperating with said screw to be slid in opposite directions thereby, and cushioning means for the opposite ends of said cup.

12. An electric stop motion device for looms comprising a guide roller formed of a cylindrical casing, an axle bearing at one end thereof, a tubular screw extending into the other end of said casing upon which said casing is rotatably mounted, a fixed support for said screw, an electric terminal post carried by said support, another post carried by said screw, cooperating contacts associated with said casing and screw adapted when said casing is reversely rotated to be

brought into engagement and a plurality of pins arranged upon the periphery of said casing.

13. An electric stop motion device for looms including a rotatable casing, fixed elements arranged in spaced relation therein, a movable contact within said casing between the fixed elements, cushion means at opposite sides of the contact and engaging the fixed elements, a stationary contact associated with said casing, cushioning means for the stationary contact, and means for causing the movable contact to engage the stationary contact.

14. An electric stop motion device for looms including a rotatable casing, longitudinal key-way slots formed upon the inner face thereof, a contact slideable in said casing and having lugs extending into said slots, a stationary contact associated with said casing, and means for holding the movable contact at the limit of movement in one direction out of engagement with the stationary contact when the casing is rotated in a clockwise direction, said holding means operating upon a reverse rotation of the casing to slide the movable contact in the casing into engagement with the stationary contact.

15. An electric stop motion device for looms including a rotatable casing, longitudinal key-way slots formed upon the inner face thereof, a contact slideable in said casing and having lugs extending into said slots, cushioning means at each side of said contact, a stationary contact associated with said casing, and means for holding the movable contact at the limit of movement in one direction out of engagement with the stationary contact when the casing is rotated in a clockwise direction, said holding means operating upon a reverse rotation of the casing to slide the movable contact in the casing into engagement with the stationary contact.

16. An electric stop motion device for looms including a rotatable casing, longitudinal key-way slots formed upon the inner face thereof, a contact slideable in said casing and having lugs extending into said slots, a stationary contact associated with said casing, means for holding the movable contact at the limit of movement in one direction out of engagement with the stationary contact when the casing is rotated in a clockwise direction, and cushioning means for holding the stationary contact normally projected, said holding means operating upon a reverse rotation of the casing to slide the movable contact in the casing into engagement with the stationary contact.

In testimony whereof I affix my signature.

WASYL LAWURUSHKO.
